AMPLIFIED CHECK GAGE

Anthony J. Martin, Livonia, Mich., assignor to Charles J. Martin & Sons, a corporation of Michigan

Application September 7, 1954, Serial No. 32,173

Term of patent 14 years

(Cl. D52—1)

Fig. 1 is a front elevational view of an amplified check gage embodying my new design;

Fig. 2 is a rear elevational view;

Fig. 3 is a side elevational view;

Fig. 4 is a top plan view;

Fig. 5 is a bottom view; and

Fig. 6 is a view in perspective.

The essential features of the design reside in the portions shown in full lines.

I claim:

The ornamental design for an amplified check gage, substantially as shown and described.
